United States Patent

Des. 237,237
Patented Oct. 21, 1975

237,237

BOOK HOLDER

Madeline Nelson, 203 Jefferson St.,
Rockwell, Iowa 50469

Filed Sept. 14, 1973, Ser. No. 397,600

Term of patent 14 years

Int. Cl. D6—99

U.S. Cl. D6—184

FIG. 1 is a perspective view of a book holder showing my design.

FIG. 2 is a plan view of the book holder design of FIG. 1, reduced in scale from the design of FIG. 1.

FIG. 3 is a side elevation view of the book holder design of FIG. 2.

FIG. 4 is an end view of the book holder design of FIG. 2.

FIG. 5 is an end view of the underside of the book holder of FIG. 2.

FIG. 6 is a side view of the underside of the design of FIG. 2.

FIG. 7 is a perspective view of another embodiment of the design.

I claim:

The ornamental design for a book holder, as substantially shown and described.
